[57] CLAIM

The ornamental design for a cutting board and storage
unit, as shown and described.

DESCRIPTION

FIG. 1 is a top plan view of a cutting board and storage
unit showing my new design;

FIG. 2 is a side elevational view, the opposite side ele-
vational view being a mirror image thereof;

FIG. 3 is a bottom plan view;

FIG. 4 is a front elevational view;

FIG. 5 is a rear elevational view;

FIG. 6 is a top perspective view thereof; and,

FIG. 7 is a bottom perspective view thereof.
